UNITED STATES PATENT OFFICE.

RALPH V. SAGE, OF COLUMBUS, OHIO.

METALLIC BOX-CAR.

1,110,403.

Specification of Letters Patent. Patented Sept. 15, 1914.

Application filed May 1, 1914. Serial No. 835,591.

To all whom it may concern:

Be it known that I, RALPH V. SAGE, a citizen of the United States, residing in the city of Columbus, in the county of Franklin and State of Ohio, have invented certain new and useful Improvements in Metallic Box-Cars; and I do hereby declare the following to be a full, clear, and exact description of the invention, such as will enable others skilled in the art to which it appertains to make and use the same.

My invention relates to railway cars and more particularly to freight box cars which are constructed entirely of metal, this construction having been shown and not claimed in my Patent No. 1,059,770, dated April 22nd, 1913, filed Aug. 3rd, 1911.

The principal objects of my invention are to produce an end wall for a metal box car which can easily be constructed, is light in weight, and of sufficient strength and rigidity to withstand the rough usage to which a car of this kind is subjected.

Another object of my invention is to construct the ends of the car of flanged plates of substantially angular form, the flanges of which are riveted together on the inside of the car in such a manner as to form an interior end frame.

Still another novel feature is to stiffen the exterior of the end wall by means of flanged end braces which extend horizontally across the ends of the car with their ends bent and attached to the car side plates thus making the ends of the car of great strength as compared with the amount of material used.

An embodiment of my invention is shown in the accompanying one sheet of drawings, in which like characters indicate like parts.

Figure 1 illustrates in elevation the end of the car showing my improved manner of bracing the same. Fig. 2 is a longitudinal sectional plan taken on the line II-II of Fig. 1, and Fig. 3 is a side elevation of the end of the car.

Referring now to the various characters of reference upon the drawings, the ends of the car are made up of four plates 1 with

inwardly extending flanges 2 and 3 acting as inside stakes or braces. These plates 2 are angular in form, the flanges 3 in the center and the end or corner edges of the car are vertical while the intermediate flanges 3 incline inwardly toward the center of the car from the end sill 4 until they reach the roof 5, to which they are secured.

Horizontal end braces 6 extend across the outside ends of the car and attached thereto with their ends bent at right angles as at 7 and riveted to the sides 8 of the car.

Although I have shown and described my improvements in considerable detail, I do not wish to be limited to the exact and specific details shown and described, but may use such substitutions, modifications or equivalents thereof as are embraced within the scope of my invention or as pointed out in the claims.

Having thus described my invention, what I claim and desire to secure by Letters Patent is:

1. A railway car, having its ends constructed from a plurality of metal plate sections of varying width, said plates being attached together along their meeting edges by means of integral inturned flanges, which act as the inside stiffening members of the car, flanged end-braces extending horizontally across the outer ends of the car and attached thereto.

2. In a railway car, having its ends constructed from a plurality of metal plate sections of varying width, said plates being attached together along their meeting edges by means of vertical and inclined integral inturned flanges which act as the inside stiffening members of the car, flanged end-braces extending horizontally across the outer ends of the car with their ends bent at right angles and attached to the sides of the car.

In testimony whereof I hereto affix my signature in the presence of two witnesses.

RALPH V. SAGE.
